CLAIM

The ornamental design for a basket for a wall with built-in home appliances, as shown and described.

DESCRIPTION

FIG. 1 is a front perspective view of the basket for a wall with built-in home appliances showing our new design;

FIG. 2 is a front view thereof;

FIG. 3 is a rear view thereof;

FIG. 4 is a left side view thereof where the right side view is a mirror image;

FIG. 5 is a top plan view thereof;

FIG. 6 is a bottom view thereof;

FIG. 7 is a reference view showing the state of use that the belt which is equipped in the internal has been detached; and,

FIG. 8 is a reference view showing the state of use that the internal goods has been stably fixed and stored by using the belt.

The broken lines are for the purpose of showing environmental structure, and form no part of the claimed design.

1 Claim, 8 Drawing Sheets
